ROBERT BOUTET, OF PARIS, FRANCE, ASSIGNOR TO LA SOCIETE FRANCAISE DES GLYCERINES, OF PARIS, FRANCE.

PROCESS FOR DISTILLATION OF GLYCERIN.

1,318,533.

Specification of Letters Patent.

Patented Oct. 14, 1919.

Application filed May 22, 1918. Serial No. 236,023.

To all whom it may concern:

Be it known that I, ROBERT BOUTET, citizen of the Republic of France, and resident of Paris, France, 28 Rue de Richelieu, have 5 invented a new and useful Process for Distillation of Glycerin, which improvements are fully set forth in the following specification.

This invention relates to a process by means of which the distillation of glycerin 10 can be carried out under particularly favorable conditions.

According to the improved procedure, the glycerin is distilled by atomizing it by means of steam, nitrogen, air or other suitable gaseous fluid, in a chamber, heated to 15 about 180° C., as distinguished from the methods heretofore employed in which the glycerin was merely distilled in a still. The known method has the drawback that as distillation proceeds the liquid becomes more and more thick and more and more impure, the result being that some of the glycerin is lost, the distillate is less pure, and the yield 20 of the apparatus less high. The present process completely obviates all of these objectionable features.

An apparatus in which the improved process may be carried out is illustrated in the accompanying drawing, but such apparatus 30 forms no part of the present invention since it constitutes the subject matter of my companion application Serial No. 236,024, filed concurrently with the present case.

In the drawing, Figure 1 is a side elevation and Fig. 2 a plan view of the apparatus, and Fig. 3 is a diagrammatic view, on an enlarged scale, of a portion of the atomizer.

Referring more particularly to the drawing, the apparatus therein represented comprising 40 a sheet metal cylinder A containing glycerin, in the interior of which there is arranged a concentric cylinder B in which the atomizing action takes place.

In the vessel A, the glycerin is heated by 45 a suitable coil and raised to a temperature of about 180° C. The vessel is supplied in a continuous manner by vacuum feed, and the level of the glycerin is maintained constant owing to the provision of a float 50 valve C.

The vessel A communicates with a water condenser through a pipe D, so that impurities volatilized below 180° C. can escape into

the condenser. The vacuum is regulated to a given value by a valve E arranged in the 55 pipe D.

The vessel A also has a vacuum gage L, a drain cock F and a pipe G terminating in a rose which conveys glycerin to the atomizer 60 H. The vessel B, or atomizing chamber, has a drain valve I connected to a collecting drum for the residues which are produced as distillation proceeds and which must be discharged without stopping the action. 65 This vessel B communicates at its top, through a pipe S, with a series of condensers, and also carries a vacuum gage K.

The atomizers H, three of which are shown, are mounted on the top of the vessel 70 A at the apices of an imaginary equilateral triangle inscribed within an imaginary circle described from the center of said top with a radius equal to two-thirds of that of the atomizing chamber. The atomizers are 75 vertically arranged, and their jets are directed downward.

Feed of glycerin to the atomizers is obtained and insured, on the one hand, by the pipe G with the rose, and on the other hand 80 by an injection of steam through a pipe M and by a regulation of the difference of vacuum between the vessels A and B, which regulation is effected to suit the difference 85 of level of the atomizers and of the glycerin, and in accordance with the output to be obtained.

In operation, the glycerin in the vessel A is heated by the coil therein, to a temperature of approximately 180° C., the level of the 90 glycerin being maintained constant by means of the float valve C. From the said vessel A, the glycerin is supplied, by way of pipe G, to the several atomizers H which, in turn, extend into the central vessel or chamber B 95 wherein the atomizing takes place. Both vessels A and B are under vacuum, but to different degrees, this difference in degree being utilized to effect, in part, the passage of the glycerin from the outer or heating vessel A to the inner vessel B, and being regulated according to the difference of level between the atomizers and the surface of the glycerin. The pipe M, by supplying 100 steam to the atomizers, also serves to effect 105 the feed of the glycerin thereto, and in addition acts in the usual way to effect the actual

atomizing operation. As distillation proceeds, the impurities, if any, which are volatilized below 180° C. in the vessel A, will escape therefrom through pipe D into the 5 water condenser, while the residues collecting in the vessel B are discharged through the drain valve I into the drum collector. The distilled glycerin, on escaping from the atomizers, becomes condensed in a series of 10 suitable condensers.

I claim as my invention:

The herein-described process of distilling glycerin, which consists in heating it to a

temperature of approximately 180° C., atomizing it while in such heated state by injecting a stream of gaseous fluid under pressure into it, separating the residues, and condensing the atomized glycerin. 15

In testimony whereof I have signed this specification in the presence of two subscribing witnesses. 20

ROBERT BOUTET.
